CLAIM

The ornamental design for a body worn condom container, as shown and described.

DESCRIPTION

FIG. 1 is a front, top and side perspective view of the body worn condom container showing my new design in the closed condition;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof; and,

FIG. 6 is a bottom plan view thereof.
